TELEPHONE DIAL MASK

Harry Simon, New York, N. Y.

Application July 9, 1941, Serial No. 401,575

1 Claim. (Cl. 179—90)

This invention relates to telephones and deals more particularly with the dialing means on the instrument thereof.

The telephone subscriber's records of the calls made during a period frequently are at variance with the number of dialed calls billed for by the telephone company for that period. This discrepancy is a frequent source of friction and annoyance both to the subscriber and the company, caused, perhaps, by the fact that the subscriber's tally is usually much less than is shown on the bill.

Upon complaint, the company will place a check upon a telephone for a short period of, perhaps, five or six days to determine with what degree of accuracy the subscriber's records are kept. The subscriber has no knowledge as to the period of the check which, if it shows any variance with the subscriber's records, will be used to discredit such records. This places the entire onus upon the subscriber and instead of clearing the atmosphere tends to aggravate the irritation between the parties concerned.

The present invention seeks to remove the mentioned source of friction by compelling a mode of tallying the calls made which will be acceptable to both the subscriber and the company. For this purpose, it is contemplated to mask the dial of the instrument in such a manner as to prevent the dialing of a telephone number but permit the calling of the operator. By such an operation, the subscriber, when a number is desired, dials the operator, asks for the desired number, and is connected by the operator who records the completed call. This record is employed for billing purposes. Thus, should a discrepancy show between the subscriber's records and the number of calls billed, examination of the operator's records will determine which is correct.

The above set-forth purposes of the invention are realized in the physical embodiment thereof illustrated in the accompanying drawing, which, while preferred, is intended as exemplary only. The following detailed specification, which has basis on the drawing, describes the invention in its present conceived form.

In the drawing:

Fig. 1 is a face view of a telephone dial fitted with a mask in accordance with the invention.

Fig. 2 is a side view thereof as associated with a telephone instrument which is shown in fragmentary form.

Referring to the drawing in greater detail, the telephone instrument 5 is provided in the usual manner with a dial 6, a finger-stop 7, and conventional indicia carrying means which comprises

the ring 8 enclosing the indicia parts 9. The dial, in the conventional manner, is formed with spaced apertures 10, one of which, designated 10^a, is the "operator" aperture and reveals such indicia at 11.

5 The ring 8, in its present form, is provided with means such as the prongs 12 which engage the dial 6 to hold said ring thereon.

The mask, as at present conceived, comprises a disc 13 of a diameter approximating that of 10 the dial 6 and having a central opening 14. The mask thus provided, is formed with a single aperture 15 located, as will be explained, to register with the aperture 10^a of the dial 6. The mask is also formed with slots 16 arranged to receive 15 the prongs 12 of the ring 8.

Made in the above manner, the mask is applied to the dial by first removing the ring 8, placing the mask upon the dial 6 with the apertures 10^a and 15 in register, and replacing the ring 8 by passing the prongs 12 thereof through the slots 16 and snapping them into engagement with the dial.

In the above manner, all of the dial apertures, except the aperture 10^a, are masked so that the 25 dial may be employed only for calling the operator as contemplated by the invention.

If desired, the mask may be locked to the dial to prevent surreptitious removal. One manner of accomplishing this is to provide a seal comprising a wire 17 which is arranged to pass through certain of the dial apertures 10 and through holes 18 formed in the mask and whose free ends are embedded in a sealing member 19. This locking means is particularly effective because of its flat condition which enables it to pass beneath the finger-stop 7 when the operator is being dialed.

It should be understood that the particular structural details may be varied, the essentials 40 of the invention residing in a dial mask having a single aperture in register with the "operator" aperture of the dial and which is mounted to move with the dial.

I claim:

45 A new article of manufacture comprising a thin flat member adapted to be placed in masking position upon a telephone dial, said member having an outer periphery similar in size and shape to that of a telephone dial, having at least two 50 slots adapted to be engaged by the prongs of the indicia member retaining ring of a telephone dial, and having a single aperture so related to said slots as to expose only the "operator" aperture of a telephone dial.

HARRY SIMON.
